Inventor:
Philip B. Downing

By Geo. K. Woodworth

Atty.

Patented May 19, 1925.

UNITED STATES PATENT OFFICE.

PHILIP B. DOWNING, OF EVERETT, MASSACHUSETTS.

COMBINED WRITING TABLET AND COPYHOLDER.

Application filed September 18, 1923. Serial No. 663,389.

To all whom it may concern:

Be it known that I, PHILIP B. DOWNING, a citizen of the United States, and a resident of Everett, in the county of Middlesex and State of Massachusetts, have invented a new and useful Improvement in Combined Writing Tablets and Copyholders, of which the following is a specification.

The present invention which is an improvement on the desk appliance described in my U. S. Letters Patent 1,269,584 dated June 18, 1918, relates to combined writing tablets and copyholders, and its object is to provide a simple device whereby a roll of paper may be supported horizontally for writing stenographic or other notes, and then raised to vertical or inclined position for transcription of the same.

With this object in view my invention comprises a suitable plate or base member supported by side members which terminate in brackets extending forwardly and rearwardly of the plate, and axles removably secured in said brackets, the rearward axle being arranged to receive a roll of paper and the forward axle slotted or otherwise constructed to receive the end of said paper, together with means for the manual rotation of said axles to wind the paper from one on to the other.

Transverse strips slightly raised from the plate may be employed to guide the paper across the plate, the forward plate serving as a line indicator during transcription and either of them as a straight edge for tearing off a strip of paper.

My invention comprises also a bracket pivotally connected to the side members for holding the plate in elevated position, and means whereby said bracket may be secured in its inoperative position parallel to the side members.

One embodiment of my invention is shown in the drawings accompanying and forming a part of this specification in which—

Figure 1 is a plan view of a combined writing tablet and copyholder embodying my invention;

Fig. 2 is a vertical section taken on the line 2—2 of Figure 1;

Fig. 3 is a side elevation showing the device in elevated position for the transcription of notes.

In the particular drawings selected for more fully disclosing my invention 10 is a plate of sheet metal supported by the side

members 11, and in the present instance the said side members are provided with ears 12, 12 near the ends thereof which are slotted to receive the plate 10, although of course 60 it will be understood that the plate may be attached to the side members in any other suitable manner.

The side members extend beyond both ends of the plate and terminate in the slotted brackets 13, 14 in which are removably secured the axles 15, 16, respectively.

In the present instance a pair of springs 17 soldered or otherwise secured to the forward bracket 13, bear against the ends of 70 the axle 15 which extend beyond the bracket 13, the ends of said springs preferably being bent around said axle as indicated at 18 to maintain the latter in position and to put the proper tension on the paper web 23. 75

Arms 19 slotted to receive the projecting ends of the axle 16 are attached to the rearward bracket 14 by the thumb-nuts 20, so that by loosening the latter said axle and the roll of paper 21 carried thereby may 80 readily be removed from said bracket.

It will be understood of course that the springs 17 or the slotted arms 19 may be used for both brackets, and that various other means may be employed for removably 85 securing the axles to said brackets.

The forward axle 15 which preferably is slotted as indicated at 22 for receiving the end of the paper 23 is provided with a crank 24 on one end thereof and a knurled-head 90 25 on the other, or with other suitable means for rotating the same, and the rearward axle 16 may be provided with similar means, such, for example, as the crank 26.

Strips 27, 28 extending across the plate 95 and slightly raised therefrom serve to guide the paper across the plate, and as straight edges to assist in tearing a strip from the web of paper, while the forward strip 28 performs the additional function of line indicator during transcription of the notes written on the web.

Transverse rods 29 may be employed to stiffen the structure and prevent the side members from spreading.

In order to hold the device in elevated position for the transcribing of the notes, a bracket 30 is pivotally connected to the side members, the legs of said bracket terminating in a disc 31 through which one of the 110 rods 29 passes. The said bracket is held in its operative position as shown in Fig. 3 and

in its inoperative position illustrated in Fig. 2 with its legs parallel to the side members 11 by means of friction discs 32 arranged to clamp to discs 31 against the side members, said friction disc being actuated by means of the wing-nuts 33, blocks 34 soldered or otherwise secured to the inner faces of the friction discs being interposed between said discs and the side members and acting 10 as fulcrums.

In operation the user of my improved writing tablet and copyholder will draw off a length of paper from the roll 21, insert the same under the strips 27, 28 and thread 15 the end thereof through the slot 22 in the forward axle, and then after the exposed portion of the paper resting on the plate, or a portion thereof, has been used, will reel off from the roll 21 a fresh portion by rotating the forward axle.

To transcribe the notes written on the web the device is placed in the position shown in Fig. 3 and by retrograde rotation of the rearward axle, the portion of the web on 25 which the notes have been written are reeled off the forward axle on to the roll 21 until the first line of said notes appears above the strip 28, whereupon the notes are transcribed line by line, a slight turn of the 30 handle 24 or head 25 serving to bring a new line into view above said plate.

If desired to preserve the notes written on the web, the axle 15 may be inserted

through a cylinder of wood, pasteboard or the like, suitably slotted to receive the end 25 of the web, so that the web may be rolled thereon, and when used up, the axle removed from its bracket and withdrawn from said cylinder, which may then be stored away for future reference. 40

Having thus described an illustrative embodiment of my invention without however limiting the same thereto, what I claim and desire to secure by Letters Patent is:—

A combined writing tablet and copyholder 45 comprising in combination a plate, side members supporting said plate and extending beyond both ends thereof, said side members terminating in slotted brackets, an axle arranged in the slots in each of said 50 brackets, the rearward axle being arranged to carry a web of paper and the forward axle to receive the end of said paper, a pair of springs each having one end secured to one of said brackets and bearing against the 55 axle carried by the bracket to which it is secured to restrain the rotation thereof and tension said web, the free end of each of said springs being bent around said axle to maintain the latter in position, and means 60 whereby said axles may be rotated manually.

In testimony whereof, I have hereunto subscribed my name this 17th day of September, 1923.

PHILIP B. DOWNING.
